UNITED STATES PATENT OFFICE.

EDWARD D. GODDARD, OF CANTON, SOUTH DAKOTA.

WHEEL-PULLER.

1,260,369.

Specification of Letters Patent. Patented Mar. 26, 1918.

Application filed June 20, 1917. Serial No. 175,911.

To all whom it may concern:

Be it known that I, EDWARD D. GODDARD, a citizen of the United States, residing at Canton, in the county of Lincoln and State of South Dakota, have invented new and useful

5 Wheel-Pullers, of which the following is a specification.

The subject of this invention is a wheel puller designed for removing pulleys, fly 10 wheels or the like from their shafts, and the objects of the invention are, first, to provide a wheel puller adjustable to various sizes and styles of wheel, second, to provide a simple and efficient wheel puller.

15 With the foregoing and other objects in view which will appear as the description proceeds, the invention resides in the combination and arrangement of parts and in the details of construction hereinafter described 20 and claimed, it being understood that changes in the precise embodiment of the invention herein disclosed, can be made within the scope of what is claimed, without departing from the spirit of the invention.

25 A practical embodiment of the invention is shown in the accompanying drawing, wherein:

Figure 1 is a side elevation of a pulley constructed in accordance with my invention, 30 showing the same applied to a pulley, the reversed position of the legs indicated in dotted lines.

Fig. 2 is a plan view of the same.

Fig. 3 is a side elevation of a modified 35 form of the device.

Referring to the drawing by numerals of reference:

The device as herein shown, consists of a cross head 1 which has a longitudinal slot 2 40 extending throughout its length. Within the slot 2, and positioned at the center of the crosshead, is a member 3 which is interiorly threaded to receive a screw 4 provided with a head 5 to which a wrench may be applied. 45 The sides of the cross head 1 may be spread as at 6 to receive the member 3 which is secured to the cross head in any suitable manner.

A link 7 is loosely mounted on each end of 50 the cross head and is retained thereon by a pin 8 which passes through each end of the cross head. An arm 9 passes through the slot 2 and link 7 at each end of the cross head and each arm is provided with a series 55 of apertures 10 arranged longitudinally of the arm. A pin 11 is inserted through one

of the apertures of each arm and engages the cross head 1 to hold the arm in adjusted position. The arms are also adjustable transversely because of the loose links 7 60 which will permit the arms to be moved along the cross head but, when force is applied at the lower ends of the arms tending to separate them, the links will bind against the cross head and arms and keep the arms 65 from moving. Each arm is formed at one end with a laterally extending finger 12 which is adapted to contact the face of a wheel or pulley 13 to draw it from its shaft 14. 70

When the pulley or wheel is so constructed as to permit the ends of arms 9 to pass within the rim of the wheels, and the exigencies of the case are such as to make it necessary or desirable, the arms 9 may be reversed, as 75 indicated in dotted lines Fig. 1, and the fingers 12 will then extend outwardly under the rim of the wheel.

The modification shown in Fig. 3 is exactly the same as the structure just described 80 except that instead of the arms 9, arms 9' are substituted, which are in the form of bolts, the threaded ends of which are adapted to enter threaded holes formed in the pulley 13'. As will be apparent, this form of 85 the device is intended for use on those pulleys or wheels which are supplied with threaded apertures.

In practice the device is used as follows:

The arms 9 are moved along the cross head 90 1 until they rest against the periphery of the pulley with the fingers contacting a face of the pulley. The screw 4 is then turned to force the cross head away from the end of the shaft and so pull the pulley off. 95

Where the pulley or wheel is formed with spokes or suitable openings and the wheel is mounted in a confined space or for other reasons, it is not desirable or practical to have the arms pass without the periphery of the 100 wheel, then the arms may be turned as indicated in dotted lines to engage the rim of the wheel.

When the pulley is in a confined space and is provided with threaded openings the form 105 shown in Fig. 3 is made use of. The operation of removing the pulley is the same in each case.

Having described the invention, what is claimed as new and sought by Letters Patent is:

1. A wheel remover comprising a cross

head provided with a longitudinal slot, wheel gripping arms slideable in the slot, a link loosely embracing each arm and the cross head, and a shaft contacting screw 5 threaded in the cross head.

2. A wheel remover, comprising a cross head provided with a longitudinal slot, arms sliding in the slot, a link loosely embracing each arm and the cross head, a wheel engag-

ing finger on each arm, and a shaft contacting screw threaded in the cross head.

In testimony that I claim the foregoing as my own, I have hereto affixed my signature in the presence of two witnesses.

EDWARD D. GODDARD.
